FIG. 2

FIG. 5

FIG. 6

FIG. 6: A perspective view of a rectangular frame structure, similar to FIG. 5, but with a different pattern on the top and bottom edges. The top and bottom edges are composed of a series of diagonal segments connecting vertical segments, creating a stepped or zigzag pattern. The left and right edges are solid vertical lines. The corners of the frame are rounded. The overall shape is slightly wider on the right side.

FIG. 7

FIG. 7: A perspective view of a rectangular frame structure, similar to FIG. 5, but with a different pattern on the top and bottom edges. The top and bottom edges are composed of a series of diagonal segments connecting vertical segments, creating a stepped or zigzag pattern. The left and right edges are solid vertical lines. The corners of the frame are rounded. The overall shape is slightly wider on the right side.
